PROTECTIVE SOCK WITH TUBULAR MARGINAL AIR ENCLOSURE HAVING VALVE MEANS

Douglas Thomas Mowbray, Waterloo, Iowa

Application June 12, 1948, Serial No. 32,606

1 Claim. (Cl. 36—8.1)

1

This invention relates to protective enclosures for human extremities or portions thereof and particularly to a sock-like device adapted to provide a moisture tight enclosure for a foot or an entire lower limb or the like.

During the course of treatment of an injury or ailment which is more or less localized in a foot or other portion of the leg, it is frequently necessary to employ bandages, tape, plaster casts, or medicated compresses or the like which must remain in place for an extended period of time. During such period of time, the patient frequently finds bathing a difficult task to accomplish without wetting or contaminating the bandages or other wrappings.

Also, it is frequently desirable, during treatment of the injured or ailing member with medicated compresses, that the compress be kept in a saturated condition. If the patient is bedfast, this is not too great a problem but even then precautions must be taken to protect the bedding and covers. However, if the patient is otherwise able to move about, it is generally difficult and a great inconvenience to keep the compress wet and at the same time protect objects with which the bandages may come into contact.

It is accordingly a primary object of my invention to provide a simple, sanitary, moisture-proof, sock-like device which may be used to envelope a human foot or leg to either exclude moisture or the like while bathing or retain moisture or medicaments as desired or required by the nature of the treatment being given.

Another primary object of my invention is the provision, in such a moisture-proof sock, of a novel, simple and very practical means for sealing the opening through which the foot or limb is inserted.

Still other objects of my invention are the provision of a sock-like protective member of this nature which is adapted to adjust itself to fit a wide range of foot or leg sizes and adapted to be adjusted to form a moisture-tight enclosure about any foot or leg within its size range without restricting circulation in that member.

A further object of my invention is the provision of a device of this nature which may be manufactured and marketed at a relatively low cost.

Other and further features and objects of the invention will be more apparent to those skilled in the art upon a consideration of the accompanying drawing and following specification, wherein are disclosed several exemplary embodiments of the invention, with the understanding,

however, that such changes may be made therein as fall within the scope of the appended claim, without departing from the spirit of the invention.

5 In the drawings:

Figure 1 is a side view of a sock-like member constructed in accordance with one embodiment of my invention and adapted to serve as a moisture-proof enclosure for the foot.

Figure 2 illustrates the manner in which the device of Figure 1 is used to envelop the foot.

Figure 3 represents a vertical, transverse section of my device illustrating, in particular, the means and manner of sealing the opening through which the foot enters the sock.

Figure 4 is a view taken looking at the inner face of a turned down marginal portion of the structure and shows the structural details of the air check-valve.

20 Figure 5 illustrates the preferred method of fabricating my protective device, and

Figure 6 shows a modified form of my invention.

Referring now to these drawings and to Figures 25 1 and 2 thereof in particular; as stated hereinbefore, a moisture resistant, sock-like enclosure member of the type with which this application deals may be of various lengths and take various shapes to best serve its purpose. Thus, one form of my device may be of such length as to envelop substantially the entire leg.

Another form of the device may be of such size as to envelop the fore part only of the foot. Still another form of the invention, and the one which will be described in this specification as a representative type, is illustrated in full lines by the numeral 12 in Figure 2.

This embodiment of my invention is adapted to encase the entire foot and ankle and consists, 40 in general, of a loose fitting, sock-like lower portion 13 having an inflatable, annular, cuff-like sealing portion 14 encircling or forming the open end of the sock through which the patient's foot is inserted. The inflatable tube portion, which is

45 adapted to form a pneumatic seal between the sock and leg, carries a check valve 16 through which air may be pumped, by any suitable means, to cause the inner wall portion 141 of the cuff to be forced into intimate contact with the patient's leg as best shown in Figures 2 and 3.

The check valve 16 is shown in greater detail in Figure 4 and consists of a circular disk 161 of hard or semi-hard plastic or the like cemented or sealed along a narrow marginal portion 162 thereof to the outer surface 142 of the inflatable

3
seal. The disk is apertured centrally thereof as at 163 and the film forming the wall 142 of the seal is also apertured at one or more points 164—164 within the area outlined by the marginal seal 162 but out of line with the central aperture 163.

A bulb-type pump or syringe such as that indicated at 17 provides a satisfactory and readily obtainable means for inflating the tubular seal 14. Such a pump commonly incorporates the necessary check valves, and the hose 171 should preferably be provided with a tapered nozzle of a size to provide a good fit in the aperture 163 of the check valve. Air, forced by the pump through the orifice 163, passes into the circular space between the disc 161 and the wall 142 and thence through the holes 164. Upon removal of the pump, the pressure within the tubular cuff forces the wall 142 against the port 163 to thereby seal it. A blunt object such as a match stick may be employed to release the air when necessary. This is accomplished by inserting the match stick in the aperture 163 and pushing the wall 142 away from the valve disc 161.

In the manufacture of the device herein described, a relatively thin, tough, pliable and transparent material should preferably be employed. I have found that the necessary characteristics may be had in a variety of materials but particularly among the newer plastics. Among these, I have found the elastomeric type of plastic sheeting or film to be particularly satisfactory. Other materials may be employed as for example rubber sheeting or the sock may be produced by the dipped latex method.

A preferred method of fabrication is illustrated best by Figure 5 in which a pair of blanked-out forms or sheets of material generally of the shape shown are peripherally sealed together as at 143 except for the top edge 144. The apertures 164 (see Figure 4) are punched in one sheet only near the upper edge 144 (Figure 5) and the check valve disk 161 sealed in place against the inner side thereof. A cuff is now formed in the material adjacent the open end of the device by folding the top portion 142 down along the line 145 and the cuff is completed by sealing the entire upper edge 144 to the adjacent side walls as at 146.

Although other means may be employed, I have found, particularly when plastic film is employed, that the preferred method of sealing the joints is by means of short wave electronic heating.

The modified form of my invention illustrated in Figure 6 is substantially the same as that previously described except that the cuff 18 is in the form of two or more narrow interconnected air chambers 181 and 182 both of which may be inflated through a single check valve 19. This form of the device may be fabricated in the same manner as that shown in Figures 1 to 5 but an additional, peripherally extending seam 21 is formed between the walls 183 and 184. A gap 211 between the ends of this seam permits the passage of air from one chamber to the other.

This construction has the advantage, under

4
certain conditions, that there is a lesser tendency to form striations or wrinkles on the inner wall 183 against the patient's leg.

5 A sock-like envelope or enclosure embodying my invention is well adapted to protect surgical dressings on the foot from becoming damaged or contaminated by water during bathing. This device also makes it possible to keep wet dressings in proper condition without constant attention and without serious inconvenience to the user. The cuff may be only partially inflated when used to cover wet dressings so as to cause no interference with circulation in the leg.

10 My device need not be closely or accurately fitted to the foot or leg of the user since it will readily adapt itself to a wide range of sizes due to its pneumatic cuff. This same feature makes a moisture-tight seal possible without restricting circulation in the patient's leg.

15 20 The opening for entry of the foot, in a device such as I have described, may be larger than is possible if, for example, the sock employed an elastic top. This feature also increases the ease with which the sock may be put on an injured 25 foot or removed.

20 30 Although I have described specific embodiments of my invention, it is apparent that modifications thereof may be made by those skilled in the art. Such modifications may be made without departing from the spirit and scope of my invention as set forth in the appended claim.

I claim as my invention:

35 A surgical stocking comprising a liquid-proof enclosure of sock-like shape constructed of thin, pliable, elastic material, a wide marginal portion 35 of the stocking adjacent the leg opening thereto being folded downwardly in overlapping relation with the leg portion of the stocking and sealed thereto along the edge of said marginal portion 40 to provide a relatively large tubular air enclosure expandable inwardly by air pressure to provide a pneumatic seal against a leg encased therein and valve means comprising an apertured disc 45 peripherally sealed to the outer face of the downwardly folded wide marginal portion, the said wide marginal portion also having a vent hole therethrough offset from the aperture in the disc but within the peripheral seal to the disc and adapted to seal against the inner face of said disc.

DOUGLAS THOMAS MOWBRAY.
